UNITED STATES PATENT OFFICE.

LEONCE L. BATTU, OF NEW YORK, N. Y., ASSIGNOR TO RATEAU STEAM REGENERATOR COMPANY, A CORPORATION OF WEST VIRGINIA.

STEAM-REGENERATOR.

1,097,836.

Specification of Letters Patent. Patented May 26, 1914.

Application filed October 7, 1912. Serial No. 724,280.

To all whom it may concern:

Be it known that I, LEONCE L. BATTU, a citizen of the United States, and a resident of the city, county, and State of New York, 5 have invented Improvements in Steam-Regenerators, of which the following is a specification.

My invention relates to steam regenerative apparatus and it has for its object the 10 provision of an improved regenerative apparatus wherein there may be a desired pressure range different from the back-pressure range upon the source of fluctuating steam supply. In this way I am enabled, whilst 15 maintaining only such variation of pressure as is desirable on the source of fluctuating steam flow, to increase the variations of pressure within the regenerator, and thus enlarge its capacity for supplying steam during 20 periods in which the supply to the regenerative apparatus is small or shut off.

In such installations as have heretofore been made the back-pressure on the intermittently-acting engine has had practically 25 a fixed relation to the pressure in the steam-space of the steam regenerator, so that the back pressure on the primary engine has the same range as the pressure of the regenerated steam. By my invention I adjust the 30 difference of pressure between the steam-space of the regenerative apparatus and the source for supplying steam to said apparatus according to the pressure of steam within the regenerative apparatus, increasing 35 this pressure difference when the steam-pressure in the regenerative apparatus falls below a certain point. This makes available a range of pressure within the regenerative apparatus which heretofore was impractical 40 to employ, because it is undesirable for the pressure of the source to go substantially below atmospheric pressure, so that in previous apparatus this factor fixed the minimum for the pressure on the secondary side 45 of the regenerator. More specifically, I have provided a regenerative apparatus having two steam passages leading from the source of supply, one of these passages leads the steam a considerable depth below a body of 50 water within the regenerative apparatus, while the other leads the steam to a point under water at considerably less depth or head. By opening and closing the last mentioned passage according as the steam-pres-

sure in the regenerative apparatus is relatively high or low I am enabled to vary the resistance or pressure-drop within the regenerative apparatus so that when the pressure is low within the regenerative apparatus there is a relatively large pressure-drop 55 in the steam before reaching the steam-space therein, while if the pressure is relatively high within the regenerative apparatus there is a relatively small pressure-drop of the steam before it reaches the 60 steam-space.

The drawing accompanying this specification illustrates in diagrammatic manner a system embodying one specific form of my invention.

1 is a source of fluctuating steam-flow, as for example, an intermittently-acting engine supplying widely and rapidly fluctuating exhaust steam. 2 is a passage for this steam. 3 is a regenerator supplied by this steam. 4 70 is a passage leading therefrom to carry the regenerated steam to its point of use.

5 is, for example, a steam turbine communicating with condenser 6. The regenerator is supplied with a relief valve 7 which 80 fixes the maximum pressure permitted within the regenerator and therefore the maximum back-pressure permitted on the source 1.

8 is piping leading from the supply pipe 85 2 to the regenerator and located therein at a considerable depth within the body of water 9 in the regenerator. The pipe 8 within the regenerator is supplied with numerous outlets 10, as is well understood in the art, 90 to cause the steam to be divided as it enters the water and to get into intimate contact therewith and to promote circulation thereof. 11 is a second pipe similarly entering the regenerator and provided with similar openings 10, but this pipe is, as shown, located within the regenerator at a higher level in the water.

12 is a valve controlling the opening and closure of piping 11, this valve being controlled by the movement of diaphragm 13 which is forced upwardly by the pressure of steam within the regenerator, the regenerator being connected in the space below the diaphragm by the pipe 14. The pressure 105 necessary to raise the diaphragm may be adjusted by varying the position of the weight 15 upon the lever 16 through which

the weight presses downward upon the diaphragm and opposes the pressure of the steam beneath the diaphragm.

As a specific illustration of the operation and utility of my invention let us suppose that the source 1 is an intermittently-acting engine supplying exhaust-steam normally at atmospheric pressure to the pipe 2. We may assume that a back-pressure of slightly more than three pounds above atmosphere upon this intermittently-acting engine will not substantially interfere with its efficient operation in which case the relief valve 7 may be set to open at a pressure of three pounds. At this pressure of three pounds within the regenerator the back-pressure upon the source would only be a fraction of a pound due to the low pressure required to force the steam through a small depth of water through the openings 10 of the pipe 11, the valve 12 being open at that time because the regenerator pressure is high. We may assume that the low-pressure turbine 3 could work satisfactorily through a range of pressure of say six pounds. In this case it will increase the capacity of the regenerator and therefore generally increase the economy of the plant if the regenerator can have a six pounds range of pressure. On the other hand, it is not desirable that the pressure on the source 1 should fall below substantially atmospheric pressure. By adjusting the valve 12 so that when the pressure in the regenerator is not substantially above atmosphere the valve 12 closes, the steam from the source 1 must all pass through pipe 8 and after passing through the openings thereof must pass through a considerable depth of water. This head of water can be adjusted to correspond to about three pounds drop of steam pressure, so that while the steam-pressure in the steam-space of the regenerative apparatus and of the steam supplied to the turbine varies from atmosphere to three pounds vacuum, the pressure of the steam at the source is varying between atmosphere and three pounds above atmosphere.

It is to be understood that while the specific embodiment of my invention herein illustrated shows the pipings at different levels in the same body of water, I do not desire to be limited to this precise arrangement, a single tank being shown as a simple, convenient embodiment of my invention. I also desire it to be understood that I have illustrated certain details which are not essential to my broad invention as herein-after claimed and that while I have given specific figures for illustration these are only illustrative and may be widely departed from without causing any departure from the principle of my invention. I also desire it to be understood that the regenerator should be supplied with such accessories as

are common to such regenerators, these not having been illustrated herein because they are well known to the art.

Having thus described my invention, what I claim as new and desire to protect by Letters Patent, is:

1. In a steam regenerative apparatus, the combination of a container, a heat-retaining medium in said container, means for conducting steam into said container and means acting upon change of pressure in said container for changing the resistance to the passage of said steam into said container. 75

2. In a steam regenerative apparatus, the combination of a container having liquid therein, means for introducing steam into said liquid and means controlling the resistance to steam flow into said liquid inversely proportional to the regenerated steam pressure in said container. 80

3. In a steam regenerative apparatus, the combination of a container having liquid therein, means for introducing steam to be regenerated into said liquid at different levels, the depth being inversely proportional to the regenerated steam pressure. 90

4. In a steam regenerative apparatus, the combination of a container, a heat-retaining medium in said container, means for conducting fluctuating steam into said medium at different levels and means operatively dependent upon the rate of supply of said fluctuating steam for controlling the level of introduction of said steam into said medium. 95

5. In a steam regenerative apparatus containing water, the combination of means for delivering steam into said water and means acting upon change of pressure within said apparatus for varying the depth within the water at which said steam is delivered. 105

6. In a steam regenerative apparatus containing water, the combination of piping at different levels in said water serving to deliver steam therein and means for causing the steam to be delivered through said piping at different levels. 110

7. In a steam regenerative apparatus containing water, the combination of piping at different levels in said water serving to deliver steam therein, and means for causing the steam to be delivered through said piping at different levels according to the steam pressure within said apparatus. 115

8. In a steam regenerative apparatus containing water, the combination of steam piping having numerous openings at different levels in water, and means for causing the steam to be delivered into the water through openings at one level or through openings at another level. 120

9. In a steam regenerative apparatus, the combination of steam piping having numerous openings at different levels in water, and means for causing the steam to be delivered into the water through openings at one level or through openings at another level. 125

liver, through openings at one level or through openings at another level according to the steam pressure within said apparatus.

10. A steam regenerator having steam distributing channels disposed in a body of liquid at varying depths.

11. In a steam regenerative apparatus containing liquid, the combination of piping directing steam at various depths into said liquid and valve mechanism controlled by the regenerated steam pressure for selecting the steam passage.

12. In a steam regenerative apparatus two steam passages adapted to direct steam into said apparatus and a pressure controlled valve adapted to control the passage of steam in one of said passages.

13. In a steam regenerative apparatus, the combination of piping adapted to lead a fluctuating flow of steam thereto, piping adapted to lead steam therefrom having a pressure range corresponding to that in the regenerative steam space, and means for causing the steam in the first-mentioned piping to have a lower pressure range than the pressure range in the regenerative steam space.

14. In a steam regenerative system, the combination of a source of fluctuating steam flow, a steam utilizing apparatus, an intermediate regenerative apparatus and pressure controlled means for varying the relation between the pressure at said source and that at the steam utilizing apparatus whereby the latter pressure may vary through a greater range than the former.

15. In a steam regenerative system, the combination of a regenerative apparatus containing water, a source of fluctuating steam in communication with said water at different levels, steam-utilizing apparatus in communication with the steam space of said regenerative apparatus, and means controlling the level of communication of said source with said water whereby the range of pressure on said source and that of said steam space are independent of each other.

16. In a steam regenerative system the combination of a source of fluctuating steam, a steam regenerative apparatus containing water, a plurality of communications between said source and said water at different heads therein, and means operatively dependent upon the pressure in said regenerative apparatus for controlling said communication.

17. In a steam regenerative system, the combination of a source of fluctuating steam supply, steam-utilizing apparatus, a steam regenerative apparatus having one side connecting with said source and the other side connecting with said utilizing apparatus, and means decreasing the resistance to said fluctuating steam through said regenerative apparatus proportional to the rate of supply

of said fluctuating steam, whereby the range of back-pressure on said source is less than the range of pressure of said regenerative apparatus.

18. In a steam regenerative system the combination of a source of fluctuating steam supply, a steam-utilizing apparatus, a steam regenerative apparatus between said source and said steam-utilizing apparatus, comprising a container, a heat-retaining medium therein, piping for conducting said fluctuating steam into said medium at different levels, and means operatively dependent upon the rate of supply of said fluctuating steam for controlling the piping through which said steam is conducted into said medium.

19. In a steam regenerative system the combination of a source of fluctuating steam supply, means to regulate the pressure of said source which consists in means for introducing said steam into a body of liquid in the regenerative apparatus at different depths dependent upon the pressure in the regenerated steam chamber of said regenerative apparatus.

20. In a steam regenerative system, the combination of a source of fluctuating steam supply, a steam regenerative apparatus containing water, piping connected with said source and adapted to deliver steam under said water, piping also connected with said source and adapted to deliver steam under water at a greater head than said first piping and a pressure controlled valve controlling the passage of steam to said last-mentioned piping.

21. In a steam regenerative system, the combination of a source of fluctuating steam, a steam regenerative apparatus containing water, piping connecting with said source and adapted to deliver steam under said water, piping also connected with said source and adapted to deliver steam under water at a greater head than said first piping, a valve controlling the passage of steam to said last-mentioned piping and means actuated by decreasing pressure within said apparatus to close said valve.

22. In a steam regenerative system, the combination of a source of fluctuating steam, a steam regenerative apparatus containing water, piping connected with said source and having openings therein located within said water, piping also connected with said source and having openings located within water at a greater head than said first piping and a pressure controlled valve controlling the passage of steam to one of said piping.

23. In a steam regenerative system, the combination of a source of fluctuating steam, a steam regenerative apparatus containing water, piping connected with said source and having openings therein located within

said water, piping also connected with said source and having openings located within water at a greater head than said first piping, a valve controlling the passage of steam 5 to one of said piping and means actuated by a change of pressure within said apparatus to operate said valve.

24. In a steam regenerative system, the combination of a source of fluctuating steam- 10 flow, a steam regenerator containing water, piping connected with said source and adapted to deliver steam under said water, piping also connected with said source and adapted to deliver steam under said water 15 but at a higher level therein, and a pressure-controlled valve controlling the passage of steam to said last-mentioned piping.

25. In a steam regenerative system, the combination of a source of fluctuating steam- 20 flow, a steam regenerator containing water, piping connected with said source and adapted to deliver steam under said water, piping also connected with said source and adapted to deliver steam under said water but at a 25 higher level therein, a valve controlling the passage of steam to said last-mentioned piping, and means actuated by decrease of pressure within the regenerator to close said valve.

30 26. In a steam regenerative system, the combination of a source of fluctuating steam-flow, a steam regenerator containing water, piping connected with said source and having openings therein located within the 35 water, piping also connected with said source and having openings located therein within the water but at a higher level therein, and a pressure-controlled valve controlling the passage of steam to said last-mentioned piping.

27. In a steam regenerative system, the combination of a source of fluctuating steam-flow, a steam regenerator containing water, piping connected with said source and having openings therein located within the 45 water, piping also connected with said source and having openings located therein within the water but at a higher level therein, a valve controlling the passage of steam 50 to said last-mentioned piping, and means actuated by decrease of pressure within the regenerator to close said valve.

28. In a steam regenerative system, the combination of a steam regenerative apparatus, a source of fluctuating steam, two passages therefrom leading into said apparatus, and means for closing one of said passages upon change of pressure within said regenerative apparatus.

30 29. In a steam regenerative system, in combination, a steam regenerator, a source of fluctuating steam-flow, two passages therefrom leading into the regenerator, and

means for closing one of said passages upon change of pressure within the regenerator. 65

30. In a steam regenerative system, the combination of a source of fluctuating steam, a steam regenerative apparatus supplied thereby and pressure controlling means for varying the pressure drop between said 70 source and the regenerative steam space of said apparatus.

31. In a steam regenerative system, the combination of a source of fluctuating steam flow, steam regenerative apparatus supplied thereby and means actuated responsive to diminished steam pressure within the regenerative apparatus for increasing the pressure drop between said source and the steam space of said regenerative apparatus. 80

32. In a steam regenerative system, the combination of a source of fluctuating steam supply, steam regenerative apparatus connected therewith, steam-utilizing apparatus in communication with the steam space of 85 said regenerative apparatus and pressure controlling means for limiting the range of pressure on said source below that of the steam space of the regenerative apparatus.

33. In a steam regenerative system, the 90 combination of a source of fluctuating steam supply, steam utilizing apparatus, a steam regenerative apparatus adapted to receive said fluctuating steam on one side and supply regenerated steam to said steam utilizing apparatus from the other side, and means whereby the relative pressure ranges at opposite sides of said regenerative apparatus may be different.

34. In a steam regenerative system, the 100 combination of a source of fluctuating steam supply, steam utilizing apparatus, an intermediate regenerative apparatus and means for varying the relative pressure ranges at opposite sides of the said regenerative apparatus dependent upon conditions in the steam space of said regenerative apparatus. 105

35. In a steam regenerative system, the combination of a source of fluctuating steam supply, steam utilizing apparatus, a regenerator adapted to receive steam from said source and supply steam to said utilizing apparatus, means in said regenerator whereby the range of back pressure on said source and the range of pressure of the regenerated 110 steam may be different and means whereby the difference between the ranges of said pressures may be varied.

In testimony whereof, I have signed my name to this specification, in the presence 115 of two subscribing witnesses.

LEONCE L. BATU.
